UNITED STATES PATENT OFFICE.

HARRY LEE BRUCE, OF PORTLAND, OREGON.

HOT-WATER HEATING SYSTEM.

956,677.

Specification of Letters Patent.

Patented May 3, 1910.

Application filed March 1, 1909. Serial No. 480,786.

To all whom it may concern:

Be it known that I, HARRY LEE BRUCE, a citizen of the United States, and a resident of Portland, in the county of Multnomah and State of Oregon, have invented a new and useful Improvement in Hot-Water Heating Systems, of which the following is a specification, reference being had to the accompanying drawings as constituting a part 10 thereof.

My invention has for its object to provide an efficient heating apparatus comprising a short primary circuit of water circulating directly from and to the boiler and a secondary circuit of water which is heated by the primary circuit passing therethrough, and to include in such apparatus means for insuring a uniform supply of water in the primary circuit by equalizing the expansion 15 and contraction thereof due to the opposite extremes in temperature between its outleading and inleading courses, and to insure further that the water, in that end of the secondary heating circuit with which the radiators are connected, will be constantly maintained at a high temperature and be unaffected, to any great extent, by the comparatively low temperature of the return end 20 of the secondary circuit.

My improvement is carried out in practice by making the primary circuit a pipe issuing from and returning to the boiler, and leading such primary circuit pipe through a horizontally positioned pipe of larger cross 30 section, which pipe constitutes the casing for the heating chamber of the secondary circuit with which the radiator pipes are connected.

Figure 1 shows a diagrammatic representation of the installation of my improvement in a building; it being understood that parts not shown, for example the stand pipe and expansion tank in the upper part of the building, are understood to be provided as 40 usual; Fig. 2 is a larger scale, sectional detail of the left end of the secondary heating chamber, and of the corresponding portion of the primary circuit pipe, and also shows a portion of the return pipe connecting the 45 radiator with the left or return end of the secondary heating chamber; and Fig. 3 is a sectional detail illustrating the arrangement of the parts at the right end of the secondary heating chamber.

From the top of the boiler, α , extends the primary circuit pipe, b , from which the

courses b' , b^2 , b^3 lead back to the boiler. This pipe, as will be noted, is of short circuit, and the water therein circulated will, in consequence, be of high heating efficiency. 60 The horizontal course b' of the pipe b is inclosed by a pipe or jacket e , of larger diameter, which constitutes the casing of the water heating chamber of the secondary circuit of my system, and the ends of said casing e are closed by any convenient means adapted to have the primary circuit pipe extended therethrough. At the top of the right end of the secondary heating chamber e is connected a riser h , leading to the 70 radiators g in the upper stories of the building, and the bottom of the left end of the secondary heating chamber e is connected by a pendent course f^2 of the return pipe f leading from the radiators g . The end f' 75 of the pipe f extends to another radiator, or other connection of the circulating system, as usual.

i is an equalizing pipe connecting the outleading and inleading courses of the primary circuit pipe b , as common in heating systems of the character described.

The details of construction not particularly described are understood to be approximately arranged as usual in a type of hot water heating system diagrammatically illustrated by Fig. 1.

The course b' of the primary circuit pipe b , inclosed by the casing of the secondary heating chamber e , has two orifices, one c at the top of its right end, and the other d at the bottom of its left end. The top opening c is located at the upper end of the perpendicular section of the pipe b , being thus located nearest the boiler, and the bottom opening d is preferably located approximately over the point of connection of the course f^2 of the return pipe f with the casing e . The purpose of the orifices c , d is to provide an outlet and inlet from and into the course b' of the primary circuit, and in so doing to take care of and equalize the incidental expansion and contraction of the water in such primary circuit.

It is to be noted that by reason of the considerable length, the comparatively small cross sectional area, and the horizontal position of the heating chamber of the secondary circuit, and the fact that the hottest and coolest water portions therein contained are located at the opposite ends of said heating chamber and separated from each other by

an intervening volume of water, that end of the heating chamber *e* to which the pipe *h*, leading out to the radiators, is connected will always be very hot, and thus effective 5 heating conditions are assured.

j represents a section of the flooring through which the radiator pipe is led from the secondary circuit.

It is to be noted that the outlet orifice, *c*, 10 of the primary circuit pipe is located in the hottest portion of the secondary heating chamber, and the intake orifice, *d*, at the coolest end of the latter; so that if, by excessive heat and consequent expansion, water 15 is expelled through orifice *c*, which has a tendency to cause a corresponding contraction and partial vacuum at the opposite end of the primary circuit pipe, a compensating portion of water is drawn in through orifice *d* from the secondary heating chamber. 20 This arrangement assures a constant volume of water in the primary circuit pipe. Furthermore, my improvement has this advantage, that the boiler does not need such 25 close attention to avoid excessive temperature, since the latter is taken care of by me as described.

I claim:

1. In a hot water heating system, a boiler, 30 a short primary circuit pipe leading directly from and to the boiler, a casing encompassing the intermediate course of the primary circuit pipe, and constituting a secondary heating chamber, a radiator and out-leading 35 and in-leading connections between the secondary heating chamber and the radiator; and the section of the primary circuit pipe within the secondary heating chamber provided with outlet and inlet orifices located 40 relative to the hottest and coolest portions of said primary circuit, for the purpose set forth.

2. In a hot water heating system, a boiler, 45 a short primary circuit pipe leading directly from and to the boiler and including a horizontal intermediate course; a pipe-like casing encompassing the intermediate course of

the primary circuit pipe, and constituting a secondary heating chamber, a radiator and out-leading and in-leading connections between the secondary heating chamber and the radiator; and the section of the primary circuit pipe within the secondary heating chamber provided with outlet and inlet orifices located relative to the hottest and coolest portions of said primary circuit, for the purpose set forth. 50

3. In a hot water heating system, a boiler, a short primary circuit pipe leading directly from and to the boiler; a casing encompassing the intermediate course of the primary circuit pipe, and constituting a secondary heating chamber, a radiator and out-leading and in-leading connections between the secondary heating chamber and the radiator; and the section of the primary circuit pipe within the secondary heating chamber provided with outlet and inlet orifices, said orifices and said out-leading and in-leading 60 radiator connections located relative to the hottest and coolest portions of said primary circuit, for the purpose set forth. 65

4. In a hot water heating system, a boiler, a short primary circuit pipe leading directly from and to the boiler and including a horizontal intermediate course; a pipe-like casing encompassing the intermediate course of the primary circuit pipe, and constituting a secondary heating chamber, a radiator and out-leading and in-leading connections between the secondary heating chamber and the radiator; and the section of the primary circuit pipe within the secondary heating chamber provided with outlet and inlet orifices, said orifices and said out-leading 70 and in-leading radiator connections located relative to the hottest and coolest portions of said primary circuit, for the purpose set forth. 75

HARRY LEE BRUCE.
